UNITED STATES PATENT OFFICE.

MICHAEL CASHIN, OF SAN FRANCISCO, CALIFORNIA.

BOILER-TUBE EXPANDER.

SPECIFICATION forming part of Letters Patent No. 319,559, dated June 9, 1885.

Application filed August 26, 1884. (No model.)

To all whom it may concern:

Be it known that I, MICHAEL CASHIN, of the city and county of San Francisco, and State of California, have invented an Improvement 5 in Boiler-Tube Expanders; and I hereby declare the following to be a full, clear, and exact description thereof.

My invention relates to the class of boiler-tube expanders; and it consists in a novel 10 manner of constructing the head of the implement to fit the sectors of the expanding-block thereto, and in the particular mechanism for imparting a rotary movement to said implement.

15 The object of my invention is to provide a simple and effective implement for fitting the boiler-tubes to the seats in the heads of the boiler.

20 Referring to the accompanying drawings, Figure 1 is a perspective view of my implement, a portion of the rim of head C being broken away. Fig. 2 is a longitudinal section of same. Fig. 3 is an end elevation of same, showing lever mechanism.

25 A is a cylindrical block divided into any suitable number of sectors, (here shown in three,) and having mounted in its surface the rollers B, forming an annular series, each roller lying parallel with the axis of revolution of the cylindrical block.

30 C is the head, made up of an annular band inside and a plate outside, separated to form a slot, as shown, and suitably joined together by means of a peripheral band. This head is provided with radial guides c. The end of the block A is provided with flanges a and grooves a'. The flanges fit within the slot of the head, whereby the block is prevented from coming out, and the grooves are fitted upon 35 the radial guides, whereby the sectors of the block are adapted to be guided in expanding.

40 D is a wedge having radial wings d. This wedge fits into a correspondingly wedge-shaped socket made in the inner end of the block, the wings of the wedge fitting suitable grooves in the socket.

45 A screw, E, passes through the hub of the head, and through the center of the block into the wedge. By the operation of this screw 50 the wedge is drawn into its seat for the purpose of expanding the block.

Around the inner end of the block is a spring, F, to hold the sections of the block together, and to act against the wedge in returning the block to its position.

55

Upon the hub of the head C are two ratchets, G, the teeth of which are arranged in opposite directions. Between these ratchets, upon the hub of the head, is a loosely-playing lever, H, to which are pivoted on opposite 60 sides spring-pawls I, adapted to engage each with one of the ratchets. These pawls are operated by oscillating the thumb-shaft J, provided with wings j, in such a manner that when the thumb-shaft is turned in one direction 65 one of the pawls is raised away from its ratchet and held in disengagement, while the other pawl is allowed to spring to its engagement with the other ratchet, whereby the lever is adapted to turn the whole device in 70 one direction.

By the movement of the thumb-shaft in the other direction the first pawl springs to its engagement with its ratchet, while the pawl previously in engagement is thrown out, thus 75 adapting the lever to turn the device in the other direction.

K is a nut screwed upon the end of the hub of the head, for holding the outer ratchet in place. The usual practice in fitting the tubes to their 80 seats in the heads of the boiler is to drive wedges into their ends, and then insert a tapering rod by the hammering of which the tubes are extended to snugly fit their seats; but this operation is imperfect in its results 85 and takes considerable time.

In operating my implement the block is inserted in the end of the tube. The screw is then operated to draw its wedge into its socket, thus expanding the block to the required extent, in order to cause the rollers to bear against the walls of the tube. The lever is then operated to turn the whole device, whereby the tubes are expanded equally and effectively.

To remove the implement, the screw is operated to force the wedge back, thus allowing the spring to contract the block, whereupon it may be readily removed.

Having thus described my invention, what I claim as new, and desire to secure by Letters 100 Patent, is—

1. In an implement, tool, or machine for

expanding the ends of boiler-tubes, the head C, consisting of an outer disk and an inner ring, separated to form a peripheral slot, and held together by an encircling band, said head 5 having radial guides c, in combination with the cylinder-block A, composed of sectors having flanges a on their rear ends fitting within the slot of the head, and grooves a', fitted upon the radial guides c, the central 10 wedge, D, by which the block is expanded, and the screw E, by which the wedge is operated, all arranged and adapted to operate substantially as herein described.

2. In an implement, tool, or machine for 15 expanding the ends of boiler-tubes, the head C, having the peripheral slot and radial guides c, the segmental block A, having flanges a fitting in the slot of the head and grooves a' fitted on the guides c, the rollers B on the

block, the encircling-spring F, the wedge D, 20 and screw E, all as described, in combination with the ratchets G, fixed on the hub of the head and having oppositely-arranged teeth, the loosely-playing lever K, between the ratchets, the spring-pawls I on each side of the 25 lever, adapted to engage with the ratchets, and the winged thumb-shaft J, passing through the lever, to throw the pawls alternately out of or into engagement with the ratchets and reverse the direction of revolution of the implement, substantially as herein described. 30

In witness whereof I have hereunto set my hand.

MICHAEL CASHIN.
